UNITED STATES PATENT OFFICE.

WILLIAM A. SMITH, OF DETROIT, MICHIGAN, ASSIGNOR TO CHICAGO PNEUMATIC TOOL COMPANY, OF NEW YORK, N. Y., A CORPORATION OF NEW JERSEY.

ROCK DRILL.

Application filed September 30, 1921. Serial No. 504,272.

The invention relates to percussive tools of that type having a rotary motor for revolving the tool combined with the reciprocating motor for furnishing the impact. It is the object of the invention to obtain a simple and convenient arrangement of the parts and to this end the invention consists in the construction as hereinafter set forth.

In the drawings:

- 10 Figure 1 is a side elevation of the tool;
 Figure 2 is a longitudinal section on line 2—2 of Figures 1 and 3;
 Figure 3 is a cross-section on line 3—3 of Figure 2;
 15 Figure 4 is a cross-section on line 4—4 of Figure 2; and
 Figure 5 is a longitudinal section on line 5—5 of Figure 3.

A is the barrel or cylinder of the reciprocating motor; B is the piston therein; C is the drill or tool proper; D is the anvil or member which receives the impact of the piston and transmits the same to the tool C, and E is a rotary socket for holding the tool C and imparting rotary movement thereto. As has been stated, the present invention relates to that type of tool in which the rotary movement for the socket and drill is furnished by a rotary motor. This motor is fluid-operated and is preferably of the intermeshing gear type. There is also a step-down transmission mechanism between the motor and the socket which reduces the speed and increases the torque. I have de-

35 signed an exceedingly simple and convenient arrangement in which the motor is mounted at the head end of the barrel or cylinder A, while the step-down gearing is arranged in an intermediate compartment between the 40 motor and the barrel. Thus, as shown, F is the rotary motor casing containing the intermeshing gears G and G', the former being mounted on the driven shaft H extending through the casing F towards the barrel. 45 The inner wall of the motor casing is formed by a hollow casing I which forms a housing for the step-down transmission and also a spacer between the motor casing and the head J of the barrel. Within the housing 50 I the shaft H has mounted thereon a pinion K which meshes with a larger gear L and the latter is mounted upon a shaft M extending longitudinally of the barrel outside the same and provided at its opposite end with a pinion N in mesh with an annular gear O on

the rotary socket E. The shaft M is journaled in a hollow radial extension P of the barrel. Q is a throttle valve which controls the supply of motive fluid to the motor.

With the construction as thus far described, when the motor is in operation, its movement will be transmitted through the shaft H, pinion K, gear wheel L, shaft M, pinion N and annular gear O to the rotary socket E, while at the same time reciprocating movement is imparted to the piston B to deliver blows upon the anvil D, transmitting the same to the tool C. Where the tool is used as a rock drill, it is usual to provide a stream of water which flows through the axis of the tool to near the cutting edge and serves to wash away the chips. It is also usual to pass the conduit for conveying this water through the axis of the reciprocating piston and the head of the barrel. With my improved construction, the motor being arranged at the head of the barrel, is in the path of this water supplying conduit, but I have avoided this difficulty by arranging one of the gears G' of the motor in axial alignment with the barrel and by passing the water supplying conduit through the common axis. Thus, as shown, R is a water conduit extending longitudinally through the axis of the barrel and through the head J thereof. S is a lug within the housing I which is apertured for the passage of the conduit R. This permits the conduit R to extend from the outer end of the barrel inward through the motor, piston and anvil 90 and into the hollow tool C.

My construction is one which is easy to assemble as the head J, housing I and motor casing F may be successively placed in position. All of these parts are then held in fixed relation by a pair of longitudinally extending bolts U which pass through ears V in the casing F and corresponding ears in the housing V for the rotary socket E. The barrel, head J and housing I are clamped between these members and are held from rotational displacement by pins W.

What I claim as my invention is:

1. The combination with the barrel for a reciprocating piston and a rotary tool holder at one end thereof, of a rotary gear motor mounted at the opposite end of said barrel, one gear of said motor being in axial alignment with said barrel, a transmission between said rotary motor and ro-

tary tool holder including intermeshing gears, and a housing for said intermeshing gears interposed between said barrel and motor.

5. 2. The combination with the barrel for a reciprocatory piston and a rotary tool holder at one end thereof, of a rotary motor mounted at the opposite end of said barrel, a portion of said motor being in axial 10 alignment with said barrel, a transmission between said rotary motor and rotary tool holder comprising a shaft extending longitudinally of the barrel outside the same, and step-down gearing between the motor and 15 said shaft, and a housing for said step-down gearing intermediate the motor and the barrel and partly in alignment with the latter.

3. The combination with the barrel for a reciprocatory motor and a rotary tool 20 holder at one end thereof, of a rotary motor mounted at the opposite end of said barrel, a head at the latter end of the barrel, a hollow casing between said head and said rotary motor, parts of said rotary motor 25 and said casing being in axial alignment with said reciprocatory motor, and a transmission between said rotary motor and rotary tool holder including intermeshing gears housed in said hollow casing.

30. 4. The combination with the barrel for a reciprocatory motor and a rotary tool holder at one end thereof, of a fluid actuated rotary motor mounted at the opposite end of said barrel, a head at the latter end 35 of the barrel, a hollow casing between said head and motor, a transmission between said said motor and rotary tool holder including

intermeshing gears housed in said hollow casing, and a fluid conduit extending axially through the reciprocatory motor, one 40 of the rotary motor gears and the intermediate head and casing.

5. The combination with a barrel for a reciprocatory motor and a rotary tool holder at one end thereof, of a rotary motor 45 mounted at the opposite end of said barrel, a head at the latter end of the barrel, a hollow casing between said head and motor, a transmission mechanism between said motor and rotary tool holder, including intermeshing gears housed in said hollow casing, 50 said rotary motor and said hollow casing being at least partly in axial alignment with said barrel, and bolts connecting the rotary motor casing and the barrel clamping said 55 transmission housing and head for the reciprocatory motor therebetween.

6. The combination with the barrel for a reciprocatory motor, and a rotary tool holder mounted at one end thereof, of a rotary motor mounted at the opposite end of said barrel, a head at the latter end of the barrel, a hollow casing between said head and motor, a transmission between said motor and rotary tool holder including intermeshing gears housed in said hollow 60 casing and a water tube extending axially through the reciprocatory motor, one of the rotary motor gears and the intermediate 65 head and casing.

In testimony whereof I affix my signature.

WILLIAM A. SMITH.
